CHANGEOVER VALVES FOR REGENERATIVE OVENS

Franz Doll, Essen, Germany, assignor, by mesne assignments, to Koppers Company, Inc., Pittsburgh, Pa., a corporation of Delaware

Application December 6, 1952, Serial No. 324,572

3 Claims. (Cl. 202—262)

This invention relates to changeover valves for regenerative ovens, particularly regenerative coke oven batteries for changing over the direction of flow of the producer gas and waste heat with a fluid dip seal closure.

Changeover cup valves provided with a liquid dip seal give an effective and secure sealing so long as, when employed as changeover valves for producer gas and waste heat in regenerative ovens, they are filled with a liquid which does not vaporise too readily at the high waste heat temperatures. Such changeover valves with a liquid seal have, however, the disadvantage that the solid constituents of the waste gases which readily deposit on the abutment surfaces of the liquid cups contaminate the sealing cups so that in the course of time the valve seat surfaces of the gas outlet wall of the cup become encrusted and proper sealing no longer takes place.

According to the present invention this disadvantage is avoided by arranging in the sealing cups of the changeover valves annular immersion bodies occupying approximately the horizontal cross section of the same and floating on the sealing liquid and having a shape and size such that the immersion body upon the imposition of the valve disc in the sealing liquid is forced with this disc into the sealing liquid. By means of such operation of an annular floating body substantially covering the sealing liquid it is found that only negligible quantities of the solid constituent deposited from the waste gases can pass into the liquid of the immersion cups.

According to the invention the upper side of the immersion body is constructed to extend obliquely downwards and inwardly from the outer wall of the changeover valve to the upper edge of the inner gas outlet wall of the liquid cup, when the body is floating on the sealing liquid of the immersion cup with the waste heat valve opened. In this way the dust settling on the surface of the annular body drops over the gas outlet edge of the liquid cup into the waste gas passage.

According to a further feature of the invention, the immersion cup is constructed to taper conically downwards and the under side of the annular floating body is constructed to extend obliquely downwardly and outwardly to adapt it to this shape of the cup.

The invention further consists in connecting the immersion cups of all the changeover valves of one or both sides of the battery of a regenerative coke oven battery, by means of a connecting pipe connected in series with an equalising vessel for adjusting the liquid level, from which the sealing liquid, preferably at given time intervals, is pumped round through a circulation pipe.

By pumping the sealing liquid around in this way in the immersion cups of the changeover valves connected in series in the liquid line, a continuous renewal of the sealing liquid in each changeover valve is achieved. Preferably, the connecting points of the connecting pipe to the immersion cups of the separate changeover valves are arranged in the lower narrower trough portion of the conically extending part of the immersion cups, so that

2

with the high speed resulting at such narrower part, through the reduced cross section, the solids which may still accumulate in the sealing liquid are well flushed out.

One form of construction of the invention is shown by way of example in the accompanying drawing.

Fig. 1 shows a vertical section through a changeover valve, with a waste heat valve disc in a closed position, constructed according to the invention.

Fig. 2 is a section similar to Fig. 1 with the waste heat valve disc in open position.

Fig. 3 shows diagrammatically the changeover valve with a liquid circulating pump vessel.

The changeover valve is connected through the interior of its housing 1 and a branch pipe 2 with the regenerator 3, not shown in detail, which is traversed at certain time intervals by producer gas or waste heat. Through an adjacently disposed changeover valve, not shown in the drawing, air is supplied to the neighbouring regenerator, or waste heat is drawn off. The housing 1 of the changeover valve is connected at its base with a waste heat passage 4 leading to a collecting passage. Producer gas is delivered at 5 through the changeover valve when the waste heat valve 8, shown open in Fig. 2, is closed, as shown in Fig. 1. The changeover of gas and waste heat is effected in the known manner by reversal traction members, through rollers or the like (not shown in the drawing) so that when the waste heat dip valve 8 is closed, a valve 6 arranged in the gas supply pipe 5 is open and vice versa.

In the lower part of the housing 1 of the changeover valve there is also arranged a conical immersion cup 7 which is tapered to narrow downwardly and widen upwardly. In the liquid filled immersion cup 7 there is also arranged an annular immersion float body 9 which floats on surface of the liquid when the waste heat dip valve 8 is opened. The immersion float body 9 has in vertical section an upper surface 23 extending obliquely downwards from the outer wall of the housing 1 to the upper inlet extremity or gas outflow edge of the inner wall of the immersion cup 7, as can be seen from Fig. 2. The level 11 of the sealing liquid is kept so high that in this position solid constituents such as dust or the like depositing on the upper oblique surface 23 of the immersion body 9 are entrained in the stream of waste gas and taken along into the waste heat passage 4 during the outflow of waste heat.

The floating body 9 is constructed underneath in a similar manner to the upper surface of the immersion body but with the underside of the cone extending downwardly and outwardly so that it conforms substantially to the lower narrowing of the conical construction of the immersion cup 7 and can submerge sufficiently deeply into the immersion liquid therein. This immersion position can be seen in Fig. 1 and results, upon closing of the waste heat valve 8, from the application of the valve disc 8 onto the immersion body 9.

As can be seen from Fig. 3 the separate changeover valves 1 are connected in series with a liquid pipe 12 through which the sealing liquid is delivered from a container 13 through the immersion cups 7 of the individual changeover valves. A return flow pipe 15 leads finally to a pump 14 which is preferably set in circulation at definite time intervals and pumps the liquid in the container 13 in cycle through the series of valves 1.

As can be seen from Figs. 1 and 2, the connection for the inflow and outflow of the sealing liquid in the immersion cups 7 is arranged in the lower part of cups 7, so that at that region, on account of the narrower part of the tapered construction a high speed is given the liquid and in this way a good through-flushing is obtained.

The container 13 has a dividing wall 16. In the one

compartment 18 formed thereby there opens a return pipe 15 whilst in the other compartment 19 there extends an overflow pipe 20. The upper end of the pipe 20 determines, in accordance with the laws governing communicating pipes, the liquid level in the various changeover valves 1. In the compartment 18 of the container 13, there accumulate the solid constituents separating from the waste gas and these may be removed at certain intervals through a conical base 22.

The liquid level, determined by the pipe 20, is permanently maintained by the supply of fresh liquid at 24, whereby to make up for the loss of liquid. Excess liquid flows away through the overflow pipe 20.

It is, however, possible to maintain the liquid level by means of a float valve, not shown in the drawing, regulating the supply of fresh liquid.

I claim:

1. A liquid regenerator-reversing dip seal valve comprising: a housing having a regenerator connection for inflow of gas thereto from a regenerator, an outlet connection for outflow of gas from the housing, an annular cup around the outlet connection, a dip valve for the annular cup, and an annular float in the cup depressible by the dip valve on immersion of the dip valve in the cup to seal off the outlet connection to gas flow thereto from the housing; and characterized by a housing construction around the outlet connection that allows the upper part of the float to rise to a level above the inlet extremity of the outlet connection and by an upper surface for the float that extends obliquely substantially entirely across the cup in a direction downwardly to the inlet extremity of the outlet connection from a higher level above said extremity, when the float is emergent in liquid in the cup, in the open position of the dip valve, for off-flow entrainment of solid constituents that may deposit on the top surface of the float into the outlet connection, by gas flow through the housing from the regenerator connection to the outlet connection, and a downwardly narrowing lower trough portion for the cup underneath the float, combined with a liquid outlet from the cup at the lower narrower trough portion thereof, for high liquid speed flushing-out of solids that may nevertheless collect beneath the float in the cup notwithstanding the action of the oblique top surface for the float, said liquid outlet comprising an equalizing vessel, an overflow outlet therefrom, an outlet pipe from the cup in series with the equalizing vessel and discharging therein above the overflow outlet therefrom, a pump in said outlet pipe, a return line from a level in the equalizing vessel below the overflow outlet to the cup, an overflow partition at a level intermediate the overflow outlet and the return line, said

partition being disposed in the equalizing vessel between the inlet thereto of the outlet pipe from the cup and the inlet to the return pipe from the vessel, and said overflow outlet being in the portion of the vessel between the partition and the inlet to the return pipe from the vessel, for controlling the level of the liquid in the cup by the level of liquid in the equalizing vessel, a sediment outlet from the portion of the vessel between the overflow partition and the inlet to the vessel from the outlet pipe from the cup, and a fresh liquid inlet to the equalizing vessel.

2. A liquid seal valve as claimed in claim 1 and in which the float is conical in cross-section with the apex of the float alongside the outlet connection but intermediate the outlet connection and the base of the cone of the float, and in which the outlet connection is tapered to widen toward the base of the conical float to provide the narrower high liquid speed area in the cup.

3. A liquid regenerator-reversing dip seal valve comprising: a housing having a regenerator connection for inflow of gas thereto from a regenerator, an outlet connection for outflow of gas from the housing, an annular cup around the outlet connection, a dip valve for the annular cup, and an annular float in the cup depressible by the dip valve in immersion of the dip valve in the cup to seal off the outlet connection to gas flow thereto from the housing; and characterized by a housing construction around the outlet connection that allows the upper part of the float to rise to a level above the inlet extremity of the outlet connection and by an upper surface for the float that extends obliquely substantially entirely across the cup in a direction downwardly to the inlet extremity of the outlet connection from a higher level above said extremity, when the float is emergent in liquid in the cup, in the open position of the dip valve, for off-flow entrainment of solid constituents that may deposit on the top surface of the float into the outlet connection, by gas flow through the housing from the regenerator connection to the outlet connection.
